UNITED STATES PATENT OFFICE

WILLIAM K. WILSON, OF NORWALK, CONNECTICUT

FUR PLUCKING

Application filed February 24, 1930. Serial No. 430,649.

This invention relates to fur plucking and more particularly to a method of and apparatus for removing the guard hairs from furs.

5 Nature has provided fur bearing animals with guard hairs. These hairs are longer and have a different character or texture than the shorter hairs which constitute the main body of hair of a fur or pelt. Before the 10 majority of furs may be used for the garment industry or for the felt hat industry it is necessary to remove the guard hairs from the pelt. In plucked furs the value of the 15 pelts depends upon the amount of fur on the hide and the thoroughness with which the guard hairs have been removed from the hide.

The methods and machines which have heretofore been used for plucking hairs have 20 not thoroughly removed the guard hairs, some of the machines merely cutting off the guard hairs and other machines have acted to pull out and cut off a part of the hair of the pelt in removing the guard hair so that 25 the value of the pelt was materially reduced.

The primary object of the present invention is to provide a method of and apparatus for plucking guard hairs from a pelt by which the hairs may be thoroughly separated 30 from the fur and effectively pulled out of the pelt without removing fur from the pelt.

Another object of the invention is to provide a method of and apparatus for plucking fur pelts by which the guard hairs may be effectively placed in a position to be plucked, regardless of the matted or disheveled condition of the hair on the pelt.

40 A further object of the invention is to provide a method of and apparatus for plucking fur pelts by which the fur on the pelt may be arranged and restored to the condition in which it existed naturally on the animal when alive at the time the guard hairs are being removed.

With these and other objects and features in view, the invention consists in the method of and apparatus for plucking pelts herein-after described and particularly defined in 50 the appended claims.

The various features of the invention are illustrated in the accompanying drawings, in which:

Fig. 1 is a view in front elevation of a fur plucking machine embodying the preferred 55 form of the invention;

Fig. 2 is a side elevation, partly in section of the fur plucking machine;

Fig. 3 is a detailed sectional view of the 60 plucking rolls;

Figs. 4 and 5 are detailed sectional views of the pelt guide for the plucking rolls; and

Fig. 6 is a diagrammatic view of a pelt 65 between the guide and plucking rolls.

The present application constitutes a continuation in part of my copending application Serial No. 244,242, filed January 3, 1928, for fur plucking.

To pluck fur pelts in accordance with the present invention a pelt is firmly supported 70 on a guide and moved back and forth before a pair of plucking rolls which grip and pull the guard hairs out of the pelt. The pelt is supported upon and moved across the guide by hand and it is necessary to hold the pelt 75 firmly against the surface of the guide to permit the plucking rolls to grip and pull the hairs out of the pelt. The pelt is manipulated in any desired manner in order to bring all of the guard hairs of the pelt within the 80 range of action of the plucking rolls.

Referring to the drawings, particularly Figs. 1, 2 and 6, a pelt 10 is moved across a guide 12 between the guide and a pair of plucking rolls 14 and 16. The guide 12 consists of a roll which is mounted in a fixed non-rotating position between the arms of a yoke 15. The yoke 15 has a pivotal connection in each arm thereof upon pins 16' which are mounted on upright standards 18, the standards constituting the side frames of the machine. A handle or foot treadle 20 is connected to the center portion of the yoke and extends downwardly to the floor of the operating room in order that it may be operated 90 by the foot of the operator. The guide roll 12 is normally held in a predetermined fixed position against stops 22 by means of tension springs 24, which are connected between the 95 arms of the yoke 15 and lugs 26 in the stand- 100

ards 18. The stops 22 are adjustably mounted in the standards 18 in order that the position of the guide with reference to the plucking rolls may be varied.

5 Plucking rolls 14 and 16 are fixed on shafts 28 and 30 respectively, which are rotatably mounted in bearings positioned in the standards 18. On the right hand end of the shafts 18 and 30, viewing Fig. 1, are mounted spur 10 gears 32 and 34 which are intermeshed so that as shaft 28 is positively rotated in one direction, the shaft 30 will rotate in the opposite direction. The shafts 28 and 30 are so spaced that the rolls 14 and 16 are pressed together with a considerable pressure. Preferably the bearings of the shafts 28 and 30 may be adjusted, in order to vary the pressure between the rolls and to provide for wear on the bearings. The shaft 28 has a 15 portion extending outwardly beyond the spur gear 32 upon which is mounted a pulley 36. Positive rotation of the plucking rolls is obtained by means of an electric motor 38 which is connected with the driving shaft 28 20 by means of a belt 40 which extends between the pulley 36 on the shaft 28 and a pulley 42 mounted on a driving shaft 44 of the motor. It has been found that a speed of rotation of the plucking rolls slightly less than the speed 25 of rotation of the usual electric motor,—that is from 1200 to 1400 R. P. M.—gives very satisfactory results.

When carrying on the fur plucking operation it has been found best to have the operator to work while in a standing position. Accordingly the uprights 18 and plucking mechanism are mounted upon a table 46 of the proper height to support the work in a convenient position for the operator. Preferably the foot treadle 20 extends substantially to the bottom of the table legs in a convenient position for operation by the operator.

On most fur-bearing animals the guard 45 hairs are considerably longer than the hair forming the fur of the pelt. Accordingly, if the guard hairs can be raised to a position substantially at right angles to the face of the pelt, these hairs will project far enough from 50 the main hair of the fur to permit them to be gripped while being pulled out, and still not grip and pull out the hair of the fur.

An important feature of the present invention consists in the method and apparatus 55 for lifting and straightening the guard hairs as well as the fur at the time the guard hairs are being plucked, in order to place the guard hairs in position so that they may all be removed. To accomplish this, a high potential 60 electrostatic current is passed between the guide and the plucking rolls which acts to straighten and draw out the hair of the pelt between the guide and the plucking rolls.

By adjustment of the guide the distance be- 65 tween the plucking rolls and the guide may

be varied so that the guard hairs may be passed into the grip of the plucking rolls to permit the hairs to be pulled out while at the same time preventing the hair of the fur from coming within the grip of the plucking 70 rolls.

Referring to the drawing an electrostatic generating machine 50 is mounted under the table 46. One terminal of the generating machine is connected by means of a conductor 52 with the guide 12 while the other terminal of the machine is connected by a conductor 54 with the plucking roll 14. The electrostatic generating machine has substantially the same construction and mode of operation 80 as the well known electrostatic generating machines, with the exception that the present machine is made larger in order to develop higher potentials. It has been found that the best potential for operating on furs 85 lies within the limits of 1000 to 25,000 volts. The amperage of the electrostatic generating machine is very low, but this amperage may be varied within reasonable limits by controlling the speed of rotation of the generating 90 discs.

Referring to Figs. 1 and 2, generating discs 56 are rotatably mounted on a hollow shaft 58 and generating discs 60 are rotatably mounted on a shaft 62. The shafts 58 and 62 are rotated in the opposite direction by connections through means of belts 64 and 66 respectively that are driven through connections with the motor 38. The electrostatic energy generated by the machine is collected by means of collectors 68 which in turn are connected with the terminals of the generator. No attempt is made to give a detailed description of the construction and mode of operation of this machine because it forms no specific feature of the invention and the machine construction and mode of operation are substantially the same as that of the machines well known in the art.

In order that a high electric potential may be maintained between the plucking roll 14 and the guide 12 it is necessary to provide the surface of the roll and guide with a metallic conducting surface and to fully insulate the rolls from each other and from the ground, in order that the roll and guide will hold the potential. The construction of the plucking rolls is shown more particularly in Fig. 3. Plucking roll 14 consists of a shaft 28 upon which is mounted an electric bakelite insulation 70 and a cylindrical conducting surface 72. The bakelite insulator 70 is preferably made up of a series of sections of bakelite which are slidably mounted over the shaft with the two end sections secured for rotation with the shaft by means of keys 74. The sections of the bakelite between the ends of the metal tube 72 which preferably is made out of brass have a smaller outside diameter 115 than sections 76 at each end of the roll where. 120

by the outside diameter of section 76 is substantially the same as the outside diameter of the metallic tube 72. The end sections 76 are held in position on the shaft 28 by means 5 of bakelite collars 78 which are fixed to the shaft 28 by means of pins 80. A brush 82 makes a slideable contact with the cylinder 72 and is held in fixed position over the roll 14 by an arm 84 secured to the upright 18. The 10 arm 84 and holder of the brush are fully insulated with bakelite to prevent grounding the roll 14.

The roll 16 consists of the shaft 30 and a rubber roll 86 fixed thereon. The rubber roll 15 86 consists of a comparatively hard rubber which is fixed to the shaft for rotation therewith by means of keys 88. The rubber roll is maintained in fixed position on the shaft by means of bakelite collars 90 mounted at 20 each end of the roll and fixed in position by means of pins 92. The shafts 28 and 30 are so mounted in the uprights 18 that the rolls 14 and 16 are in pressure tight contact with one another so that as the rolls rotate in opposite direction, the guard hairs are firmly gripped between the metal surface of the roll 14 and the rubber surface of the roll 16 in order to positively pull the hairs out of the pelt passing over the guide 12.

30 The construction of the guide 12 is shown more particularly in Figs. 4 and 5. This guide consists of a shaft 94, an electrical bakelite insulation covering thereon 96, and brass conducting tubing 98 mounted on the bakelite tubing 96 and a bakelite guard 100 mounted on tube 98. The bakelite tubing 96 is preferably formed in sections and is held from rotation on shaft 94 by means of a key 102. The brass tubing which acts as the conducting surface for the electrostatic current fits tightly over the insulation 96 and makes a tongue and groove connection 104 with each end of bakelite insulator 96 near each end of the guide. The insulator 96 is held in fixed 40 position at the end of the shaft 94 by means of collars 106 which are secured to the shaft by means of pins 108. The shaft 94 is fixed into the ends of the yoke 15 in a nonrotatable position. The bakelite cylindrical member 100 45 covers only the rear face of the brass conducting tube 98 and is provided for the purpose of protecting the operator and preventing the electrostatic charge on the tube 98 from becoming grounded. The charge on the 50 tube 98 is conducted thereto by means of a terminal 110 as connected with the conductor 52.

In view of the fact that the guard hair and fur hair on a pelt vary in length with the 55 different kinds of animals and other conditions, it is necessary that the guide 12 should be made adjustable with reference to the plucking rolls, in order to provide for the varying lengths of hair. Preferably the 60 guard hairs should make contact with the

plucking roll 14 in order to assist the electrical potential in drawing the hair into substantial perpendicular position with reference to the plane surface of the pelt. With furs which are badly matted it may in some 70 instances be necessary to vary the electrostatic charge in order to straighten the hairs for the purpose of plucking them. The charge is usually controlled by various forms of construction of the electrostatic machines, and by controlling the rate of rotation of the plates in the machines. Furthermore, the distance between the guide 12 and roll 14 has a decided effect on the manner in which the hair 75 may be straightened by the electrostatic charge and therefore the guide may be adjusted, in order to assist in drawing the hair into proper position.

The higher voltage electrical potentials are 80 very advantageous in raising hair on the fur and accordingly it is often advantageous to use voltages that will produce a spark longer than the length of the gap between the guide 12 and the rolls 14-16. To accomplish this the electrical potential is applied to the shaft 94 and the conducting brass tubing 98 removed. In these cases the thickness of the bakelite tubing 96 is controlled to give the necessary protection against sparking while 85 using higher voltages.

90 The method of the present invention permits the use of plucking rolls of small diameter. The small diameter plucking rolls are very advantageous in gripping the guard hairs and permit the selective removal of the 95 guard hairs from the fur hair on the pelt.

100 When the hair of a fur becomes matted or disheveled, it injures the appearance of the fur. It has been found that when a fur is passed between the guide and the plucking rolls all of the hair on the pelt is affected by the electrostatic current, that it is raised and straightened, and experience has shown that when the hair has been raised and straightened by the current it does not go back to the 105 matted position, but rather goes back to the normal position which the hair naturally occupies on the live animal. This is a very decided advantage in the present machine, in that the furs which have been plucked have 110 a very fine appearance and are greatly improved by the machine. In fact, the appearance of most any fur may be improved by passing the fur between the guide and the plucking rolls, even though there are no guard 115 hairs to be plucked.

120 The electric energy for controlling or raising the hair on the fur as it is being operated upon may be generated by other means than the well known electrostatic generating machine, as for example, by means of a high voltage transformer, and any of the well known rectifiers. The well known high voltage "Kenotron" tubes used in conjunction with suitable transformers are also suitable 125 130

for generating the necessary electrical potential for raising hair on the furs.

I claim:

1. A method of plucking furs comprising continuously moving a pelt having fur and interposed hair thereon into a zone of a static electric charge to cause the hair and fur to assume an outstanding position and gripping and pulling the hair while it is maintained in outstanding position.

2. A method of plucking furs comprising moving a pelt having fur and interposed hair thereon into a zone of a static electric charge of at least 1000 volts to cause the hair and fur to assume an outstanding position and removing the hair while it is maintained in outstanding position.

3. A method of plucking furs comprising moving a pelt having fur and interposed long hairs thereon into a zone of a static electric charge to cause the hairs and fur to assume an outstanding position, continually gripping and pulling the hairs while maintained in outstanding position and supporting the pelts so that only the hair will be subjected to the gripping and pulling operation.

4. A method of plucking furs comprising moving a pelt having fur and interposed hair thereon into a zone of a static electric charge to cause the hair and fur to assume an outstanding position the voltage of the static charge being variable to provide a control of the position of hair for different kinds of pelts and removing the hair while it is maintained in outstanding position.

5. In a method of treating furs those steps which comprise moving substantially the entire surface of a pelt having fur and interposed hair thereon into a zone of electric charge of a voltage of 1000 to 25,000 volts sufficient to cause the hair and fur to assume outstanding positions on the leather of the pelt, then withdrawing the pelt from the influence of the electric charge and permitting the hair and fur to settle back to a natural position on the leather of the pelt.

6. A plucking machine comprising an insulated guide, a pair of insulated plucking rolls mounted adjacent the guide, an electrostatic machine having negative and positive terminals connected respectively with the guide and rolls, means to rotate the rolls in opposite directions with an approaching movement on the side of the rolls adjacent the guide.

7. The combination defined in claim 6 wherein a metallic conducting surface of the guide which is connected with a static charge is covered with an electrical insulator.

8. The combination defined in claim 6 wherein one of the plucking rolls has an insulated metallic conducting surface and the other roll has a yieldable surface.

9. A plucking machine comprising a guide having a metallic surface insulated from

ground by means of a series of bakelite tubes, a pair of plucking rolls mounted adjacent the guide, one of said rolls having a rubber surface insulated from ground and the other roll having a metallic conducting surface insulated from the other roll and the ground by means a series of bakelite tubes, an electrostatic machine having its terminals connected respectively with the guide and the roll having a metallic surface, and means for rotating the rolls.

In testimony whereof I affix my signature.

WILLIAM K. WILSON.
